UNITED STATES PATENT OFFICE.

ROZANDER S. HIGGINS AND WILLIS W. HIGGINS, OF NEOGA, ILLINOIS.

SLIDING OR ROLLING GATE.

SPECIFICATION forming part of Letters Patent No. 366,097, dated July 5, 1887.

Application filed August 11, 1886. Serial No. 210,638. (No model.)

To all whom it may concern:

Be it known that we, ROZANDER S. HIGGINS and WILLIS W. HIGGINS, citizens of the United States, residing at Neoga, in the county 5 of Cumberland and State of Illinois, have invented certain new and useful Improvements in Sliding or Rolling Gates, of which the following is a specification.

Our invention relates to that class of sliding 10 or rolling gates which are operated from levers by persons either walking or riding; and it consists in features of novelty, hereinafter fully described, and pointed out in the claims.

In order that our invention may be fully 15 understood, we will proceed to describe it with reference to the accompanying drawings, in which—

Figure I is a side elevation of our improved 20 sliding gate, showing it closed. Fig. II is a similar view showing it open. Fig. III is a view from the opposite side of the gate, showing it closed. Fig. IV is a section through the line $x x$, Fig. III, showing the operating-levers and their connections. Fig. V is a detail view of the locking device.

A represents the gate, which carries grooved rollers B, revolving loosely upon pins C on the uprights D. Between two bars, E, the rollers are guided, the bars being secured to 30 a post, F, a post, G, and a post, H, in a horizontal position. The latter post is extended upwardly just high enough to enable the operating-levers for opening the gate to be grasped by an equestrian without dismounting. The gate closes against the usual gate-post, F'. The post F is on the same side of 35 the guide-bars E, as is the gate A, so that when the gate is opened the post F forms a stop to prevent farther movement of the gate than is necessary. The three posts F G H are cut away at f g h, respectively, sufficiently 40 to allow the rollers to move without obstruction. At the top of the extended post H is a cross-bar, I, having pivoted at its ends levers J J'. Lever J is pivoted to a bifurcated bar, K, bent outward, and having a heel portion, k, below which are pivoted to the bar connecting-links L of the lever J' in such a manner as to allow the necessary movement there- 45 of. On the side of post H is a pin, M, on

which is pivoted, at the angle thereof, an L-shaped lever, N. The short branch of this L-shaped lever is pivotally connected by means of a rod, O, with the lower end of the bifurcated bar K. Pivoted to the lower ends of 55 the bifurcated bar K and rod O is a bar, P, for steadyng them in their movement, which is hinged to the post G on the inner side thereof. Secured to the side of the gate is a metallic or other brace, S, through which, for 60 pivoting a toggle-bar, Q, between it and the gate, is passed a screw-bolt, R, held by a nut, R'. The toggle-bar Q is pivoted to the lever N by means of two cheek-pieces or straps, Q'. At the end of the lever N is formed a pointed 65 portion, N', and the opposite corner of the lever is rounded off at N'', so that when the gate is shut the lever will move out of line with the toggle-bar Q, so as to allow the point N' to bite on top thereof when it is attempted 70 to open the gate otherwise than by the operating mechanism. The toggle being below the top of the gate in all its positions, the latter affords a brace or protecting medium therefor. To lock the gate, the toggle must 75 be to the right of a straight line drawn from the pivotal connection at the gate to that at the post, and this is accomplished only when the gate is entirely shut.

Having thus described our invention, the 80 following is what we claim as new therein and desire to secure by Letters Patent—

1. The combination, with a post having a lever pivoted thereto, and suitable means connected to the lever for operating it, of the 85 gate, a toggle-bar pivoted at the side of the gate, a cheek-piece fixed to the toggle-bar, pivotal connection between the lever and cheek-piece, and a pointed projection on the lower end of the lever, adapted to engage the 90 upper end of the toggle-bar when the gate is closed, substantially as set forth.

2. The combination, with a sliding or rolling gate having suitable operating-levers mounted on an extended post and connections, of an L-shaped lever pivoted to said post and the connections, a toggle-bar pivoted to the gate and pivotally connected to said L-shaped lever, a lock arranged between the 95 impinging ends of the L-shaped lever and the 100

toggle-bar and acting only when the gate is closed, and a bracket bolted over said toggle-bar, substantially as and for the purpose set forth.

- 5 3. The combination, with the lever N, having a pointed portion, N', and rounded portion N'', of the toggle-bar Q, pivotally con-

nected with lever N, substantially as and for the purpose set forth.

ROZANDER S. HIGGINS.
WILLIS W. HIGGINS.
